ORTHOPEDIC APPLIANCE AND BRACE

Leopold Springer, Union City, N. J.

Application May 2, 1942, Serial No. 441,456

3 Claims. (Cl. 128—71)

This invention relates to an orthopedic appliance, particularly a brace for supporting parts of the human body when support is required, and for keeping neighbouring parts of the body in proper relation.

The invention is particularly applicable when either of the companion parts constituting a joint has been injured or when one or more of them are diseased and supplemental supporting or holding devices become necessary.

Although the invention is capable to provide support for the companion parts of any joint, it is particularly of advantage in supporting the hip joint.

In the case of acute diseases of a joint, such as a fracture, it is necessary to hold the broken parts in place by means of rigid braces until the fracture has healed. Even after the healing process is completed, some weakness is apt to remain, and a support is needed until the joint is perfectly restored, and for such purpose the brace according to the invention is of utility.

In the case of acute arthritis or inflammation of a joint, particularly the hip-joint, a treatment is necessary after the acute phenomena have disappeared, and the joint is to be supported in which case the brace according to the invention is also of utility. The same applies to habitual luxation of a joint, particularly the hip joint, where such a support according to the invention is useful.

There are other cases in which the brace of the invention is applicable to advantage, whenever weakness of a joint, such as a hip joint, exists or remains from any disease or fracture, and either support of the joint or a limitation of the relative movement of the parts connected in the joint is advisable. This includes conditions resulting from diseases, such as tabes, where excessive relative movement or wobbling of the joined parts is to be prevented.

It is, therefore, an object of the invention to provide an orthopedic appliance or brace which is capable of supporting parts of the human body connected in a joint and to permit a limited motion of those joined parts but prevent their loose motion.

It is another object of the invention to provide an orthopedic appliance or brace which affords parts of the human body connected in a joint comfortable and sufficient support where such support is needed, permits a limited movement of the parts joined and also permits immobilization of these parts relative to one another.

It is still a further object of the invention to

provide an orthopedic appliance or brace in which parts of the human body connected in a joint are comfortably supported, permit a limited movement of the supported parts but also their immobilization, and which can be easily adjusted from one condition to the other to meet the wearer's comfort.

This and other objects of the invention will be more clearly understood when the specification proceeds with reference to the drawing in which by way of exemplification Fig. 1 shows perspective and with some parts broken away, the brace, and Fig. 2 a cross section along the line 2—2 in Fig. 1.

15 In the drawing a brace is shown for use at the hip joint, for example the right hip joint. It comprises an upper girdle-like supporting member 10 provided with a lining preferably of fabric and shaped to fit the abdomen of the wearer and to be closed in front. It may include elastic portions, if desired, or be elastic throughout, giving however the body and brace a firm support. The upper and lower edges may be reinforced with strips of leather or fabric 11, 12, and vertical stiffening means may be arranged at suitable places, as shown for instance at 13, 14 and 15. The stiffening means may consist of fabric or leather strips sewn to the girdle-like support 10, and they may form casings to hold flexible bones.

20 30 The edges 16, 17 for closing the support 10 are also reinforced and provided with eyelets 18 through which laces 19 are to be drawn. Any other way of closing the girdle-like support, such as by hooks and eyes or slide-fastener, may be used. A tongue 20 is preferably arranged inside the closure.

25 40 A strap 21 is fastened to the left rear part of the support 10 and to be brought over the shoulder of the wearer, and its free end is passed through a metal loop 22 and fastened to a clasp 23 which is adjustable on the strap 21. Metal loop 22 is held in place by strap 24 which is sewn to the outside of support 10.

45 50 Another part of the brace to lie on the back part of the upper thigh, in this exemplification of the right leg, consists of a flexible and preferably well padded portion 25 on which an upper and a lower belt-like tubular member or device is fastened. The upper device consists of an inner belt portion 26 and an outer belt portion 27; the lower belt-like device consists of an inside belt portion 28 and an outside belt portion 29.

55 Portion 27 may consist of leather with a lining onto which a cover 30 of leather or fabric is sewn within which a flat bar 31 of metal is held; the

bar is curved to fit the leg. At the end of portion 30 a buckle 32 is fastened by means of a sewn on loop 33 through which the tongue-like end 34 of the inner portion 26 can be passed. Portions 26 and 27 form together a tubular member which is placed around the leg and tightened by means of buckle 32 and tongue 34.

The lower tubular member or belt portion 29 consists preferably of leather lined inside, and the belt portion 28 ends in two tongues 35, 36 which can be passed through buckles 37, 38 fastened to belt portions 29 by a sewn on loop 39. On the outside of belt-portion 29 a cover 40 of leather or fabric is sewn and inside the cover 40 a flat metal piece 41 is inserted which is curved to fit the leg.

On the outside of the girdle-like support 10 and above the hip of the wearer a cover of leather or fabric 42 is sewn on and within the cover is arranged a flat metal piece 43 curved to fit the wearer's body around and above the hip. To the flat metal piece 43 the upper part of a flat brace bar is rigidly connected, for instance by means of rivets 45, having sunk heads. The bar projects downwardly within a casing of leather or fabric 46, closed by sewing at 47. Within the lower end of the casing 46 a joint member 48 is arranged to which a lower flat brace bar 49 is journaled. Bar 49 passes the cover 30 on the upper support 27 and is rigidly connected, for instance by means of rivets 50 having sunk heads, with the curved flat metal piece 31 within casing 30. The curved end of brace bar 49 enters inside cover 40 and is rigidly connected with the flat curved metal piece 41, preferably by rivets 51, having sunk heads.

Outside support 10 and rigidly connected with the curved metal piece 43, extending from the lateral front to the side above the hip a curved bar 52 is arranged and riveted or screwed at 53 and 54 to the metal piece 43. To the upper support 27, in this example on the right side of the wearer and behind the brace bars 46, 49, a buckle 55 is fastened by means of a loop 56. Another loop 57 is movably attached to bar 52 and its tongue-like end 58 passed through buckle 55.

In use, the girdle-like support 10 is put around the lower part of the wearer's torso and laced in front; the curved metal piece 43 lies around and above the right hip and the brace bars 44, 49 are on the right side. Strap 21 is slung over the shoulder and adjusted so that the support is in its proper position around the wearer's body. The upper and lower belt-like devices 27 and 29, respectively, are put around the leg and tightened by means of tongue 43 and buckle 32, and tongues 35, 36 and buckles 37, 38, respectively.

It will be appreciated that member 10 of substantially tubular form can be easily applied to the body and tightened by lacing to any desired extent, without causing discomfort to the wearer. In the same way the tubular members 26, 27 and 29 can be placed around and tightened on the wearer's leg so as to snugly embrace it without discomfort to him and interference with the blood circulation. The parts of the body joined in the hip joint are then kept in proper relation by the bars 46, 49 connected in the hinge 43 and rigidly attached respectively to the tubular member 10 and the members 27 and 29.

When loop 57 is in the position shown in full lines, strap 58 can be adjusted in buckle 55 so as to immobilize the thus supported parts of the body, i. e., that the leg cannot be swung forward

at all in the hip joint. If it is intended to also prevent swinging backwards of the leg, hinge 48 or the brace bars are to be provided with co-operating abutments in a manner well known.

5 If it is intended, however, to permit a limited movement of the leg relative to the other parts of the body, strap 58 is to be adjusted in buckle 55 so as to permit swinging the leg in the hip joint forward until the member consisting of the parts 51, 58, 55 and 56 is stressed.

If it is intended to permit the wearer to swing the leg quite freely in the hip joint so as to afford him relaxation and particularly facilitate his sitting in a chair, loop 57 is moved along bar

15 52 in the position shown in dotted lines at 60, where the member constituted by the parts 51, 58, 55, 56 either crosses hinge 48 or lies even in front of it and where in any case the stress on this member is released. It will be appreciated that bar 52 is curved in such a manner that the member constituted of the parts 51, 58, 55, 56 is stressed or nearly stressed in the position shown in full lines and thereby either immobilizes the hip joint or permits only a predetermined little or limited movement in the latter, while in the position of the same member indicated by dotted lines at 60, such limitation is either removed entirely or a considerably greater movement or forward swing of the leg in the hip joint is permitted.

It is also understood that the brace according to the invention holds the parts connected in the hip joint securely in their proper relative position and provides for proper functioning of the joint, supports the leg in the hip joint when the wearer is walking and delays his becoming tired, prevents excessive or undesirable movement in the joint and permits any relaxation without readjusting any of the parts of the brace. All the 20 wearer has to do is to move loop 57 into one of the two positions on bar 52 indicated in full and dotted lines, respectively. This he can do while all the tubular members of the brace are tightened. The brace will not show under the wearer's clothing; bar 52 can be made of any suitable material and shaped so as to lie as close as possible to the tubular member 10. A few sizes of the brace are necessary only.

Any adjustment between buckle 55 and tongue 58 can also be made, while loop 57 is in the position 60 obviously without causing pains to the wearer.

It will also be appreciated that it is easy for the wearer to change the position of loop 57 before he sits down or starts to walk and that the adjustment of buckle 55 and tongue 58 can be made once and for all.

It is understood that the principles of the invention can be used in braces for other joints than the hip joint, such as the knee, if the dimensions of the tubular members, etc., are changed accordingly.

What I claim is:

1. An orthopedic appliance or brace, comprising, in combination, two groups of tubular supporting members, each group comprised of at least one such member, two brace bars hingedly connected at one of their ends and fastened at their other ends to one of said groups each, an adjustable member connected with one of said groups, and a curved bar fixed to a tubular member of the other one of said groups, said adjustable member slidably connected with and movable into different positions on said bar, said bar 25 curved so that with a given adjustment of said

adjustable member in one of the latter's positions on said bar a swing of said groups and hinged brace bars to a greater extent is permitted than in another one of said positions.

2. An orthopedic appliance or brace, comprising, in combination, two groups of tubular supporting members, each group comprised of at least one such member, two brace bars hingedly connected at one of their ends and fastened at their other ends to one of said groups each, an adjustable and bendable member fixedly connected with one of said groups, and a curved bar connected with one of said tubular members of the other one of said groups, said curved bar extending to both sides of the brace bar fastened to the same group, said adjustable member slidably connected with and movable into different positions on said curved bar, the curvature of said bar being such that with a given adjustment of said adjustable member a swing of said groups relative to one another to a greater extent is permitted when said adjustable member is in

position on one side of said last mentioned brace bar than if it is in position on the opposite side of said latter brace bar.

3. An orthopedic appliance or brace, comprising, in combination, two groups of tubular supporting members, each group comprised of at least one such member, two brace bars hingedly connected at one of their ends and fastened at their other ends to one of said groups each, an adjustable member connected with one of said groups, and a curved bar fixed to a tubular member of the other one of said groups, said adjustable member slidably connected with and movable into different positions on said bar, said bar curved so that with a given adjustment of said adjustable member in one of the latter's positions on said bar a swing of said groups and hinged brace bars to predetermined extent is permitted while they are substantially immobilized in another predetermined one of said positions.
